(57) **CLAIM**

The ornamental design for a file cabinet, as shown and described.

DESCRIPTION

A portion of the disclosure of this patent document contains material to which a claim for copyright is made. The copyright owner has no objection to the facsimile reproduction of the patent document or the patent disclosure, as it appears in the Patent and Trademark Office patent file or records, but reserves all other copyrights whatsoever.

FIG. 1 is a perspective view of a file cabinet embodying one aspect of our new design;

FIG. 2 is a front elevational view of the file cabinet of FIG. 1;

FIG. 3 is a rear elevational view of the file cabinet of FIG. 1;

FIG. 4 is a right side profile view of the file cabinet of FIG. 1, it being understood that the left side profile view is a mirror image;

FIG. 5 is a top plan view of the file cabinet of FIG. 1; and,

FIG. 6 is a bottom plan view of the file cabinet of FIG. 1.

The subject matter shown in broken lines forms no part of the claimed design.

The broken lines shown in the drawing are for illustrative purposes only and form no part of the claimed design.

1 Claim, 6 Drawing Sheets
